MULTI-PUNCTURE INTRA-DERMAL INOCULATION INSTRUMENT

Herbert G. East, 37a Oxford Road, Cowley, England

Filed Apr. 30, 1959, Ser. No. 55,709

Claims priority, application Great Britain Dec. 16, 1958

Term of patent 7 years

(Cl. D83—12)

Figure 1 is a perspective view of a multi-puncture intra-dermal inoculation instrument embodying my new design;

Figure 2 is an elevational view thereof taken slightly to the left with respect to Figure 1;

Figure 3 is an elevational view taken from the rear of Figure 2;

Figure 4 is a top plan view; and

Figure 5 is a bottom plan view thereof.

I claim:

The ornamental design for a multi-puncture intra-dermal inoculation instrument, substantially as shown.
